UNITED STATES PATENT OFFICE

ALBERT E. WOOLNOUGH, OF ST. ALBANS, NEW YORK, ASSIGNOR TO STEPHEN SLESINGER, INC., OF NEW YORK, N. Y.

DESIGN FOR A TOY ANIMAL

Application filed November 4, 1930. Serial No. 37,527. Term of patent 7 years.

To all whom it may concern:

Be it known that I, ALBERT E. WOOLNOUGH, a citizen of the United States, residing at St. Albans, Long Island, county of Queens, and State of New York, have invented a new, original, and ornamental Design for a Toy Animal, of which the following is a specification, reference being had to the accompanying drawing, forming a part thereof.

I claim:

The ornamental design for a toy animal as shown.

ALBERT E. WOOLNOUGH.
